US0D1068888S

(12) **United States Design Patent** (10) **Patent No.:** **US D1,068,888 S**
(45) **Date of Patent:** **** Apr. 1, 2025**

(54) **CUTTING INSERT**

(71) Applicant: **NGK SPARK PLUG CO., LTD.**,
Nagoya (JP)

(72) Inventor: **Masashi Hirose**, Nagoya (JP)

(73) Assignee: **NTK Cutting Tools Co., Ltd.**, Komaki
(JP)

(**) Term: **15 Years**

(21) Appl. No.: **29/872,186**

(22) Filed: **Mar. 8, 2023**

(30) **Foreign Application Priority Data**

Sep. 28, 2022 (JP) 2022-020718

(51) **LOC (15) Cl.** **15-09**

(52) **U.S. Cl.**

USPC **D15/139**

(57) **CLAIM**

The ornamental design for a cutting insert as shown and described.

DESCRIPTION

FIG. 1 is a perspective view of a cutting insert showing my new design;

FIG. 2 is a front view thereof, a left side view, a right side view, and a rear view being identical thereto; and,

FIG. 3 is a top view thereof, a bottom view being a mirror image thereof.

1 Claim, 2 Drawing Sheets
